CANDELABRA

Marvin G. Yutzey, Moundsville, W. Va., assignor
to Fostoria Glass Company, Moundsville,
W. Va., a corporation of West Virginia

Application December 28, 1949, Serial No. 6,891

Term of patent 14 years

(Cl. D48—2)

To all whom it may concern:

Be it known that I, Marvin G. Yutzey, a citizen of the United States of America, residing at Moundsville, in the county of Marshall and State of West Virginia, have invented a new, original, and ornamental Design for Candelabra, of which the following is a specification, reference being had to the accompanying drawings, forming a part hereof, wherein:

Fig. 1 is a side elevational view of a candelabra showing my new design;

Fig. 2 is a top plan view;

Fig. 3 is an end elevational view; and,

Fig. 4 is another end elevational view thereof, viewed from the opposite direction.

I claim:

The ornamental design for a candelabra, as shown.

MARVIN G. YUTZEY.
